METHOD OF MAKING HAND-SEWN SHOES
Leonard A. Levenson, 17 Gale Ave., Haverhill, Mass.
Filed Jan. 27, 1964, Ser. No. 340,235
11 Claims. (Cl. 12—142)

This invention relates to the manufacture of footwear, in particular to hand-sewn shoes, for example shoes of the moccasin type, and more especially to a novel method of making hand-sewn shoes, such as moccasins.

In accordance with the customary procedure of making hand-sewn moccasin shoes, the vamp and insole (hereinafter referred to as the "upper") is first made customarily from a single piece of upper leather. A plug, designed to form the top of the forepart and toe portion of the moccasin, is prepared and the plug and upper are then assembled on a wooden last of selected style and size and temporarily attached to the last by tacks, and, with the last mounted upon a fixed, rigid support or "jack," the worker, provided with a thread having a needle at each end, by means of an awl, punches a hole in the upper and another in the plug at the point at which the seam is to start, and draws the thread through the holes which he has punched. He then punches another hole in the plug and another in the upper at the proper distance (stitch length) from the first holes, and passes the needles in opposite directions through these latter holes to form a stitch. He then proceeds in this manner to make holes and draw stitches (while attempting to make the stitches of uniform length) until he reaches the terminal point of the seam at the opposite side of the shoe. However, at the starting point and at the stopping point, stitches of a special type may be made to provide a pleasing finish or to prevent ravelling. It will be noted that this operation is carried out with the upper and plug mounted on a last corresponding to the style and size of the desired shoe and that it is expected that the operator will use sufficient force, in drawing successive stitches, to strain the upper snugly about the last, this being the only lasting operation performed, so that the shaping of the upper depends upon the skill and strength of the operator.

This operation is slow because the operator must punch the holes with the awl; it is laborious for the pulling of the thread tight enough to conform the upper to the last requires strength; and it is difficult because the upper, at least during the latter part of the operation, has been snugly drawn close to the last so that it is troublesome to punch the holes and to pass the needles through the holes. Furthermore, it requires a great deal of skill to maintain uniformity of stitch length so as to provide a seam of pleasing appearance. The fixed support or jack commonly employed for holding the last compels the operator to work at a disadvantage during some portions of the operation because the seam follows a generally U-shaped course. Thus, as the seam progresses around the shoe, the direction of pull in tightening the stitches almost constantly varies.

Because of the skill required in performing this operation, it is a long slow job to train an operator to do the work well and thus the manufacture of moccasins, according to this method, is expensive.

A proposed modified procedure, when hand-sewing the shoe on the last, and as a preliminary to the actual stitch formation, the upper and plug are initially provided with all of the necessary perforations, usually by means of a suitable punching die or dies. In this way it is possible mechanically to arrange the perforations regularly and at a uniform distance from the edge of the material and since in this instance the operator is not obliged to use an awl, the operation of uniting the upper and plug is facilitated, but the sewing operation still involves the pulling

2

of the stitches tightly enough to perform what amounts to a lasting operation.

A third method (but which does not produce a true "hand-sewn seam") differs from either of the two procedures just above described in that a single needle is used and the stitches are overedge stitches so that the thread overlaps the joined edges of the upper and plug where the material of the upper and plug are disposed in face-to-face relation. This operation is easier and cheaper to perform, especially with pre-perforated upper and plug, than the other two operations described, but the seam so formed is easily distinguishable from the characteristic "hand-sewn" moccasin seam, and shoes so made cannot compete for the better class trade with the true hand-sewn moccasin. Moreover, since the threads of such an over-edge seam are exposed to wear, shoes so made are prone to ravel and gap.

So far as is known, all previous methods of making true "hand-sewn shoes," as they are distinguished in the trade, 20 have depended upon the drawing of the stitches so tightly as to conform the upper to the last, that is to say, to perform the lasting operation.

One object of the present invention is to provide a novel method of making true hand-sewn shoes, in particular 25 moccasins, more expeditiously than previously but, at the same time, providing a conventional moccasin seam of fine appearance. A further object is to provide a novel method of sewing moccasin shoes such as may be performed satisfactorily by persons having but little previous 30 experience or instruction. A further object is to provide a novel method of making moccasin shoes, whereby the cost of production may be reduced substantially as compared with conventional modes of procedure.

In the attainment of the objects of the invention, the 35 upper and plug are sewn together "off of the last," that is, without attempt to conform the upper to an actual last during the sewing of the seam, and thereafter imparting shape to the assembly by force lasting.

Other and further objects and advantages of the invention 40 will be pointed out in the following more detailed description and by reference to the accompanying drawings wherein:

FIG. 1 is a perspective view of a moccasin shoe of conventional type as it appears after the completion of the 45 hand-sewn seam, by means of which the upper is secured to the forepart plug and after attachment of an outsole and heel;

FIG. 2 is a fragmentary plan view, to larger scale than FIG. 1, showing the forward portion of the combined insole and upper as having been provided with stitch-receiving 50 perforations at its margin and having been closed at the heel;

FIG. 3 is a plan view of a forepart plug of generally 55 conventional shape as it appears after having been provided with marginal perforations in accordance with the present invention;

FIG. 4 is a fragmentary section on the line 4—4 of FIG. 3, but to larger scale, showing the skived edge of the plug with the one of the stitch-receiving perforations;

FIG. 5 is a plan view of the upper and plug temporarily 60 held in assembled relation by releasable clamps according to the present invention;

FIG. 6 is a side elevation of a jack such as may be employed for supporting the upper and plug in assembled 65 relation during the sewing operation;

FIG. 7 is a fragmentary plan view, to larger scale, of the base portion of the jack, the arm which carries the form on which the shoe is sewn being broken away;

FIG. 8 is a side elevation of the jack having an assembled 70 upper and plug mounted upon the form which constitutes a part of the jack;

FIG. 9 is a fragmentary plan view, to larger scale, partly in perspective, showing an assembled upper and plug mounted upon the form carried by the jack and positioned in readiness for the sewing of the first stitch and showing removable clamping elements arranged to hold the plug and upper in proper relative position;

FIG. 10 is a view similar to FIG. 9, but showing the jack as having been turned to facilitate the formation of stitches near the toe end of the shoe;

FIG. 11 is a view generally similar to FIGS. 9 and 10, but showing the jack as having been turned still further, to facilitate the formation of stitches at the opposite side of the shoe;

FIG. 12 is a fragmentary section, to larger scale than FIG. 10, and approximately at the position of the line 12-12 of FIG. 10, showing one of the clamps holding the edges of the upper and plug together, the upper and plug being assembled on the form;

FIG. 13 is a side elevation showing the upper and plug as having been united by the sewed seam and showing the procedure whereby the lasted shape is imparted to the shoe; and

FIG. 14 is a diagrammatic plan view illustrative of a supporting block or form of variable width.

Referring to the drawings and, in particular, to FIG. 1, the character M indicates a moccasin shoe of a customary type comprising the upper or vamp 30 and the so-called "plug" 31, the plug being united to the upper by the seam 32. The shoe which is shown, by way of example, differs from a true moccasin in having an outer sole 33 and a heel 34, but it will be understood that, in accordance with the present invention, a true moccasin may be made in which the only sole is integral with the upper. As shown in FIG. 1, the shoe has an external backstay 36 and is provided rearwardly of the plug 31 with a finish bead 38 at its upper edge.

As illustrated in FIG. 2, the upper consists of a unitary piece of material, commonly a soft upper leather, which is cut to form a blank of a proper shape to make a shoe of the desired size and style. The portion 30a of this blank forms the inner sole, the blank being so manipulated as to bring two rectilinear edges together at the center of the insole area, these edges being united by a seam 35, all in customary manner. The rear end portion of the blank has its edges closed together and united by a vertical seam (not shown). In the shoe as here illustrated, this seam is concealed by an external backstay 36 which is stitched to the upper material at opposite sides of the end closure seam. The operations, thus described, result in the formation of the heel end portion of the shoe where, at opposite sides of the backstay, the material of the upper extends upwardly to form the quarter portions of the upper as shown at 30c and 30d.

At any desired point in the operation, but usually before the formation of the seam 35, the marginal edge of the upper is provided with spaced perforations 37 and is skived on its flesh side to provide a beveled edge.

The plug 31 (FIG. 3) may be of the same material or of a material different from that of the upper 30 and is a suitable shape and size to form the top of the forepart portion of the shoe. As shown in FIG. 2, the upper 30 may have distinct shoulders or corners at opposite sides as shown at 39 and the plug is of such dimensions and shape that its widest portion, when assembled with the upper, will extend from one of these corners 39 to the other and preferably with a portion 40 of the plug shaped to extend rearwardly to form a tongue, such as shown in FIG. 1, or, if the shoe is to have a throat opening, then the part 40 may be split and provided, for example, with eyelets to receive a lacing (not here shown). Forwardly from the part 40 the plug is tapered in width and provided with perforations 43 extending along its marginal edge. This marginal edge is skived (FIG. 4) on its flesh side to form a bevel in the same way as the marginal edge of the forepart of the upper. In certain types of shoes, for example

those known as "Penny Loafers," the plug may comprise a plurality of independent parts united by stitches. For example, it may comprise a transversely extending portion of the kind referred to in the trade as the "saddle," whose opposite end portions are lapped down into contact with and stitched to the upper.

The perforations in the upper and in the plug are, respectively, desirably formed by a punching operation. For this purpose, separate dies are provided, one for the upper and the other for the plug, each having a plurality of punches (preferably tubular, which may be circular or of any other desired transverse section), by means of which all of the perforations in the respective part may be formed simultaneously. The proper spacing of the perforations is first determined with respect to the plug. For example, an average spacing of approximately $\frac{3}{16}$ of an inch from center-to-center of adjacent punches produces acceptable results. However, it may be preferable to space the perforations at the wide end of the plug slightly more than $\frac{3}{16}$ of an inch apart to avoid unduly weakening the material at this point at which the greatest stress is encountered during use. On the other hand, at the toe end of the plug, where the radius of curvature is small, the spacing may be slightly less than $\frac{3}{16}$ of an inch in order to insure a smooth seam at this point. The centers of the perforations may, for example, be spaced approximately $\frac{1}{8}$ of an inch from the extreme edge of the plug.

The spacing of the punches in the die for forming the perforations in the edge of the vamp or upper is so calculated, with reference to the previously determined spacing of the punches in the die for perforating the plug, that when the plug and upper are assembled, corresponding perforations will be substantially in registry. The centers of the perforations in the upper may, for example, be spaced approximately $\frac{1}{8}$ of an inch from the extreme outer edge of the upper in the same way as in the plug. It may be desirable to space a few of the perforations at the rear end of the plug and the corresponding perforations in the upper further apart than the normal spacing in order to avoid weakening the material at the part which is subjected to the greatest stress. To provide extra strength at the ends of the seams, it is common to use special stitch formations at these points but since this constitutes no part of the present invention, such special stitch formations need not be described herein nor illustrated.

Having provided the upper as shown in FIG. 2 and the plug as shown in FIG. 3, these parts are assembled as illustrated, for example, in FIG. 5, and are temporarily united, in accordance with the present invention, by suitable clamps K. Such a clamp K is illustrated in FIG. 12 as consisting of a length of spring wire, coiled as shown at 58 to provide two normally divergent arms 59a and 59b respectively, the first-named arm terminating in a horizontal eye 60 while the other arm terminates in a hook-shaped part 61 which may be caused to enter the eye 60 by first pressing the arms 59a and 59b toward each other and then permitting them to resume their normal position in which the part 61 passes through the eye.

By the use of clamps of this type or equivalent means, the plug may be held, as illustrated in FIG. 5, in proper assembled relation to the upper so that, when thus united, the assembly or embryo moccasin may be handled as a unit.

For use in the practice of the present invention, there is provided a jack J (FIG. 6) for supporting the assembled plug and upper during the sewing operation. This jack comprises a base portion 44 (FIG. 7) designed to rest upon a table T (FIG. 8) or other suitable stationary support and which is immovably attached to the table in any convenient way, for example, by means of a screw clamp, or alternatively by bolts passing through holes 46 in lugs 45 integral with the base. The base is hollow and internally shaped to provide a socket for the reception of a two-part spherical shell 48 whose parts are held in

assembled relation by a clamping device 48b. At their meeting faces, the parts of the shell are cut away to provide a slot whose parallel edges are indicated at 47a and 47b respectively. Within this shell there is a ball B (FIG. 7) which is split diametrically, as indicated at A (FIG. 7) in a plane parallel to the opposite edges of the slot and midway between said edges. The opposed faces of the parts of the ball are recessed so as collectively to provide a radial bore for the reception of one end of a rigid rod 49. A screw-threaded clamping bolt 50 has threaded engagement with a threaded bore in the wall of the shell 48 with its inner end normally seated in a radial socket in the peripheral surface of one of the halves of the ball B, the axis of the clamping bolt being perpendicular to the plane of the split 47a in the ball. A hand wheel 51 forms the head of the bolt 50. By tightening the bolt the ball may be held stationary within the shell 48 while the shell is so expanded that it cannot turn in the base 44. By loosening the ball the shell becomes free to be oriented about the vertical axis of the base 44, while the ball is so freed that the rod 49, together with the ball, may be rocked about a horizontal axis.

The rod 49 is provided at its free end with a block or form F constituting a support for the assembled upper and plug while the seam 32 is being formed. This block or supporting form F is not a last, such as is customarily used in lasting shoes, and is not designed to give shape to the shoe which is sewn thereon. As illustrated, it has an upper surface 52 which forms a suitable support on which the plug may rest and its free end portion 53 is tapered and smoothly rounded to enter within the toe end of the upper, but the block or form F differs from a conventional last in that it is symmetrical with respect to a front-to-rear vertical plane and may be used regardless of whether the shoe being made is a right or left shoe. Furthermore, the size of this form is so selected that the assembled upper and plug, when mounted thereon, may be shifted relatively to the form if desired. This freedom of the assembled upper and plug relatively to the block or form is indicated, for example, in FIG. 12.

A sleeve member 54 is mounted to slide longitudinally of the rod 49 but is provided with a thumb screw 55 by means of which it may be fixed in adjusted position. This sleeve carries a downwardly directed arm 56 which is designed to fit within the heel end of the upper, as shown in FIG. 8, and to retain the assembled upper and plug on the form F during the sewing operation.

While the block or form F has here been shown as of unitary construction, for example of a single piece of wood, it is contemplated that, to avoid the necessity for changing forms to accommodate shoes of widely different sizes, this form may be made of two parts, that is to say, a right and a left part, united, for example, by a toggle linkage such as customarily employed in shoe "freeing" lasts or devices used for stretching footwear, so that the effective size of the form may be varied at will. Merely by way of example, such a form is illustrated diagrammatically in FIG. 14, wherein the form is shown as comprising the right and left halves F¹ and F², united by toggle linkages 60 and 61. Any suitable means (not shown) for holding them in adjusted position may be provided.

In the operation of sewing the plug and upper together, in accordance with the present invention, the upper and plug are first mulled or put in temper, as is customary in the manufacture of moccasin shoes, and then the plug and upper are assembled, as shown in FIG. 5, and temporarily united by means of the clamps K, the part 61 of a clamp being passed through corresponding perforations in the plug and upper and then through the eye 60, thus holding the plug and upper properly assembled. The number of clamps K employed may be varied, as desired, by the operator. Before mounting the upper on the form, the part 54 of the jack is moved forwardly along

the rod 49. The assembled upper and plug are then pulled over the form and the part 54, and the latter is pulled back and clamped to the rod thereby to retain the assembled upper and plug on the form.

5 The sewing is performed (FIGS. 9, 10 and 11) by the use of two needles N¹, N² through whose eyes a single thread T is passed, and the actual sewing of the seam 32 is now carried out in the customary manner. However, in accordance with the present invention, the supporting jack may first be arranged, as illustrated, for example, in FIG. 9. Before starting the seam the plug is so adjusted that registering perforations in the plug and upper are so disposed that the thread may be pulled in a substantially horizontal direction in forming a stitch, this being the most convenient position of the form for the operator to apply pulling stress in opposite directions to the thread. As the seam advances toward the toe end of the shoe, the supporting jack may be so manipulated as to bring the shoe into the position shown in FIG. 10 for example, and the clamp K, which initially was located at that side of the shoe which is being operated upon, may now be removed so as to permit the seam to advance uninterruptedly toward the toe. After the seam has passed the toe end of the upper, the shoe may, for example, be turned to the position shown in FIG. 11, further clamps being removed as the operation progresses, until the seam reaches the terminal point at which, as above suggested, special forms of stitch may be employed to prevent ravelling, all of which is customary in the art.

20 Because of the universal support for the form F, the operator may shift the form from time-to-time, so that regardless of the point at which a stitch is being drawn, the direction of the force applied for drawing the stitch will be the most convenient for him. Moreover, if he desire to perform the operation while standing, he may swing the rod 49 upwardly, as permitted by the universal support, and clamp it at any upwardly directed angle which he may find facilitates the operation.

25 When the seam has been completed, the part 54 is loosened and moved forwardly so that the shoe may readily be removed from the block or form F. The moccasin, at this stage, is not properly shaped, for it has not been subjected to any lasting operation, it being noted again that the block or form F is not a last; does not have an external shape such as to impart its shape to the moccasin; and in sewing the moccasin upon this form, the operator is not expected to exert any such stress in drawing the stitches as is customarily required when the sewing of the moccasin is depended upon to conform the upper and plug to the external surface of a last.

30 The embryo moccasin which has thus been sewn and removed from the form is now wetted until thoroughly saturated and then, as diagrammatically illustrated in FIG. 13, a last L of the size and style of the moccasin which is to be made is forced down into the wet embryo moccasin, making certain that it enters the upper properly and squarely so that, as the last is forced into the upper, the latter is trained to take the form of the exterior of the last. Thus, the moccasin is sewn "off of the last" and then force-lasting and when allowed to dry upon the last, assumes the desired shape and size. The forcing of the last into the moist embryo moccasin will draw the stitches tight and, because the perforations provided in the plug and upper were accurately spaced before sewing began, there is formed a very uniform and attractive seam, even though the stitches, as drawn, were not pulled as tightly as is usual in following the customary prior practice.

35 While a desirable apparatus and a useful sequence of steps has been described by way of example, it is to be understood that the invention is broadly inclusive of the hand-sewing of a shoe "off of the last" and of the use of any equivalent means for supporting a shoe, while being sewed, which fall within the scope of the appended claims.

40 I claim:
75 1. That method of hand-sewing the upper and forepart

plug of a moccasin shoe which comprises as steps: providing a plug having marginal, uniformly spaced stitch-receiving perforations, providing an upper having corresponding marginal perforations, assembling the upper and plug and temporarily uniting them to provide an embryo moccasin, providing a sewing thread with a needle at each end, and so adjustably supporting the embryo moccasin, while drawing stitches in the formation of a true hand-sewn moccasin seam, that the operator may apply pulling stress to the thread, in the formation of each successive stitch, in a substantially horizontal direction while starting the seam at one side of the shoe and continuing around the toe to the opposite side of the shoe, and force-lasting the shoe after completion of the seam.

2. That method according to claim 1, further characterized in that for supporting the embryo moccasin while forming the seam there is provided a form of a size and shape such that it may be entered into the embryo moccasin, but without filling the latter, and which is capable of bodily movement vertically and horizontally and of rotation about its front-to-rear axis.

3. That method of making shoes which comprises as steps: providing an upper and a plug appropriate, when assembled, to form a shoe of a selected size, the plug and upper having marginal stitch-receiving perforations, tempering the plug and upper to make them soft and pliable, temporarily uniting the plug and upper by removable fastener elements thereby to form an embryo shoe, drawing the embryo shoe over a form supported for universal adjustment as to its position, permanently uniting the plug and upper by a hand-sewn seam while progressively removing the fastener elements as the seam advances, removing the shoe from the form, and forcing a last, of the size and style of the desired shoe, into the shoe thereby to impart to the shoe the desired lasted shape.

4. That method of making a moccasin which comprises as steps: tempering a plug and upper, permanently uniting the plug and upper, while in temper and while off of the last, by a conventional hand-sewn seam and then, after thoroughly saturating with water the embryo moccasin, so formed, forcing into said embryo moccasin a shoe last of a size and shape such as to impart to the moccasin the desired lasted contour.

5. That method of making a moccasin which comprises providing a plug and upper, moistening the plug and upper, assembling the plug and upper and temporarily uniting them by means of removable fasteners, then permanently uniting the plug and upper by a sewed seam while off of the last thereby making an embryo moccasin; the fasteners being progressively removed during the sewing of the seam, saturating the embryo moccasin with water and forcing a last, of the size and style of the desired completed moccasin, into the wet embryo moccasin, and keeping the last within the moccasin until the latter has set to the shape of the last.

6. That method of hand-sewing the upper and forepart plug of a moccasin shoe which comprises as steps: providing a plug having marginal, uniformly spaced stitch-receiving perforations, providing an upper having corresponding marginal perforations, providing a form for supporting the assembled upper and plug, said form having an elongate rigid rod projecting from its rear end, providing a support for the reception of said rod such that the form may be moved horizontally or vertically or rotated about the axis of said rod, assembling the upper and plug and temporarily uniting them to form an embryo moccasin, mounting the embryo moccasin on the form, providing sewing thread having a needle at each end, passing the needles in opposite directions through registering perforations in the plug and upper, respectively, adjacent to the rear corner of the plug, and then continuing to form a true hand-sewn moccasin seam while so repositioning the form, from time-to-time, that the operator, in the formation of each stitch, may apply effective pulling stress to the thread in a substantially horizontal direction.

5 7. That method of making moccasin shoes which comprises as steps: providing an upper and a plug appropriate, when assembled, to form a moccasin of a selected size, the plug and upper having marginal stitch-receiving perforations, moistening the plug and upper, temporarily uniting the plug and upper at their forepart portions, at least, by removable fasteners to form an embryo moccasin, permanently uniting the plug and upper, while off the last, by a hand-sewn seam of the type in which two needles are employed, meanwhile progressively removing the fasteners; thoroughly wetting the embryo moccasin after completing the seam, forcing a conventional shoe last of selected size and style into the embryo moccasin thereby tightening and equalizing the stitches, and permitting the embryo moccasin to remain upon the last until it has acquired a permanent shape.

10 8. That method of making moccasin shoes which comprises as steps: providing an upper and a plug appropriate, when assembled, to form a moccasin of a selected size and style, the plug and upper having marginal stitch-receiving perforations so arranged that when the plug and upper are assembled, each perforation in the plug will register with a perforation in the upper, moistening the plug and upper, temporarily uniting the plug and upper by removable fasteners so as to form an embryo moccasin, permanently uniting the plug and upper while off the last by a hand-sewn seam of the kind which is made by the employment of two needles, meanwhile progressively removing the fasteners, and after the completion of the seam wetting the embryo moccasin and imparting to the embryo moccasin its desired lasted shape and size.

15 9. That method of making moccasin shoes with comprises as steps: providing an upper and a plug appropriate, when assembled and properly shaped, to form a moccasin of a selected style and size, the plug and upper having marginal stitch-receiving perforations so spaced that when the plug and upper are properly assembled, each perforation in the plug will approximately register with a corresponding perforation in the upper, temporarily connecting the plug and upper, to form an embryo moccasin, by means of removable fastener elements, so supporting the embryo moccasin as to permit it, while still supported, to be moved from time-to-time so as to dispose it in the most convenient position for the operator as he sews the seam, and while it is so supported, permanently uniting the plug and upper by a sewed seam of the type which is made by the employment of two needles.

20 10. That method of making a moccasin of a selected size and style wherein the upper and plug are united by a hand-sewn seam, employing for the purpose a thread and two needles, said method comprising as steps: providing a form of a size such that it may be installed in the embryo moccasin without substantially stretching the latter, the form having a tapered and smoothly rounded forward end, and an upper surface appropriate to support the plug, the form being symmetrical with respect to a vertical front to rear plane, assembling and temporarily uniting the upper and plug by temporary fasteners to form an embryo moccasin, introducing the form into the embryo moccasin, and by means of the form supporting the embryo moccasin while hand-sewing the seam and progressively removing the temporary fasteners, thoroughly saturating the embryo moccasin with water, and thereafter imparting to the moccasin, so produced, the desired lasted shape by forcing a conventional last of the selected size and style into the moccasin.

25 11. That method of making moccasin shoes according to claim 9, further characterized in that after the completion of the sewed seam the embryo moccasin, so formed, is saturated with water, a conventional shoe last is forced into it, and the moccasin is allowed to remain on the last until substantially dry.
